WINDOW STRIP INSTALLATION AND FASTENER FOR THE SAME

Wilmer H. Churchill, Saugus, Mass., assignor to United-Carr Fastener Corporation, Cambridge, Mass., a corporation of Massachusetts

Application December 14, 1935, Serial No. 54,493

2 Claims. (Cl. 296—44.5)

My invention relates to the means of attaching a window strip or the like to a support and aims to provide an improved fastener member for that purpose.

5 Referring to the drawing in which I have illustrated a preferred embodiment of my invention:

Figure 1 is a section of a window channel support, a window for the same, and a window strip secured to the support by means of the fastening 10 members which are shown in elevation;

Fig. 2 is another view of the installation shown in Figure 1 with the window strips and fastener members shown in elevation;

Fig. 3 is a view taken on the line 3—3 of Fig. 2;

15 Fig. 4 is a view taken on the line 4—4 of Fig. 2;

Fig. 5 is an enlarged view of the fastener member illustrated in Figs. 1—4;

Fig. 6 is a side view of the fastener member illustrated in Fig. 5; and

20 Fig. 7 is a rear view of the fastener member illustrated in Fig. 5.

The object of my invention is to provide a simple and inexpensive means for attaching a flexible strip or the like to a supporting structure.

25 My invention is particularly useful as a means for securing a flexible strip or trimming used in connection with an automobile window installation to the framework of the window channel. This flexible strip is of great importance if installed with an automobile window channel as it seals the space between the sides of the channel frame and the window so as to prevent to an appreciable degree the passage of air through those spaces and at the same time fur-

30 nishes a smooth anti-rattle runway for the window pane. Due to the fact that my improved clip member is particularly adaptable to the attachment of a window channel strip to a channel frame, I prefer to describe it in connection with such an installation although there are many other uses to which my fastener could be directed which would fall within the spirit of this invention.

35 Referring to Figs. 1—4, which illustrate a preferred use of my invention, I have shown a metal window channel comprising opposite frames 1, each of which is of U-shaped construction in cross-section. The oppositely disposed inside faces 2 of the frames bound the channel through 40 which the window pane 3 is moved during the raising and lowering of the same. The flexible strip 4 is positioned to seal in effective manner the passages between the frame faces 2 and the window pane, as may be clearly seen in Fig. 1.

45 The strip may be formed in any suitable manner

although I have illustrated a part of a substantially tubular construction having slightly flattened sides and an outer covering of a sturdy cloth-like material. In my preferred form I have provided the strip with a core comprising a metal 5 stiffening means 5 for preventing too great flexibility of the part. The nap means 6 extend from one side of the strip, as illustrated in Fig. 1.

The strip is attached to the frame 1 by means of my improved fastening members which are 10 provided with a stud means 7 extending through an aperture 8 in the frame face 2 and engaging in snap fastener action the material of the frame surrounding the aperture, as best illustrated in Figs. 1 and 2.

15 Referring in greater detail to the fastener member, I have illustrated in Figs. 5—7 a clip which is made from one piece of sheet metal presenting a flat base plate 9, a resilient attaching portion 11, and a hook-shaped spring clamping means 11. In my preferred form the clip is tempered to provide suitable spring action in certain of the parts, as described below.

The attaching portion of my preferred form is pressed from the material of the base plate 25 and provided with a head portion 12 and neck portion 13. The head and neck portions are rendered resiliently contractible by a plurality of slots 14, herein shown as four, which preferably, as illustrated in Figs. 5 and 7, extend to or slightly 30 into the base plate. The spring clamping means 11 is formed integral with the base plate having a hook-shaped arm 15 looped beneath the plate on the opposite side of the plate from the attaching portion. The part 15 is provided at its 35 extremity with an inturned clamping edge 16 for gripping the strip. A slot 17 extends from the base plate for a substantial distance into the part 15 for providing an easier working spring action in the clamping means.

40 In assembling the parts of the installation the flexible strip 4 is forced into the space between the arm 15 and the rear face of the fastener base plate. As the thickness of the strip is slightly greater than the distance between the edge 16 45 and the face of the plate, the arm 15 will be expanded slightly until the strip is secured in correct position, at which time the arm will contract so that the edge 16 will grip the strip to hold it firmly against the face of the plate (Fig. 50 1). The fastener is then brought up to the aperture 8 of the steel channel frame and the attaching portion 11 is extended through the aperture to engage the walls of the frame in a snap fastener action thereby causing the window strip 55

to be firmly attached in operating position. It is obvious that any number of fastener members may be used to attach the strip to the frame, but it is necessary that a corresponding number of apertures be located in correct position in the frame supports to receive the attaching portions of the fasteners.

I have shown in Fig. 1 window strips attached to opposite inside faces of the channel frame so that the trimming is located on both sides of the glass. It is common in automobiles, however, to provide a strip solely on one side of the channel, namely against the inside surface of the glass to prevent cold air or dust from entering the interior of the automobile, and for that reason I do not wish to be limited to the double window strip installation as shown in Fig. 1. Furthermore, I do not wish to be limited to the resilient stud portion, as shown, because it is possible to provide several modified constructions of this portion, any one of which would be equally satisfactory as a means for attaching the fastener to the frame support.

Although I have illustrated and described a preferred embodiment of my invention, I do not wish to be limited thereby, because the scope of my invention is best set forth in the following claims.

I claim:

30. 1. In an installation of the class described, a support having an aperture therethrough, a narrow flexible strip superposed upon said support,

a sheet metal clip, said clip having a base portion located between the support and the strip, a resilient snap fastening means extending from one side of said base portion through the aperture in said support and secured in snap fastening engagement with said support, and a hook-shaped arm connected to said base portion at one end thereof and extending over the edge and one face of said strip and being clamped against that face of said strip with the hook end embedded into the material of the strip to hold said strip securely in position relative to said support.

2. In a window installation of the class described, a window frame support having an aperture therethrough, a narrow flexible window guide strip, a metal snap fastener clip and a window slideable against said window guide strip, said clip having a base portion, a resilient snap fastening means extending from one side of said base portion through the aperture in said support and secured in snap fastening engagement with said support and a compressible clamping means including said base portion as a part thereof, said clamping means being in compressed clamped relation with said strip for securing it to said support, said clamping means having a strip-engaging portion extending therefrom toward and into embedded relation with the strip to prevent the strip from slipping laterally relative to the clip.

WILMER H. CHURCHILL.
